CLAIM

The ornamental design for a display screen or portion thereof with graphical user interface having a three dimensional appearance as shown and described.

DESCRIPTION

The file of this patent contains at least one drawing/photograph executed in color. Copies of this patent with color

drawing(s)/photograph(s) will be provided by the Office upon request and payment of the necessary fee. FIG. 1 is a front view of a display screen or portion thereof with graphical user interface having a three dimensional appearance showing the claimed design; FIG. 2 is another front view thereof, showing the front orientation of the graphical user interface; FIG. 3 is another front view thereof, showing the rear orientation of the graphical user interface; FIG. 4 is another front view thereof, showing the right side orientation of the graphical user interface; FIG. 5 is another front view thereof, showing the left side orientation of the graphical user interface; FIG. 6 is another front view thereof, showing the top orientation of the graphical user interface; FIG. 7 is another front view thereof, showing the bottom orientation of the graphical user interface; FIG. 8 is a front view of another embodiment of a display screen or portion thereof with graphical user interface having a three dimensional appearance showing the claimed design;

FIG. 9 is another front view thereof, showing the front orientation of the graphical user interface; FIG. 10 is another front view thereof, showing the rear orientation of the graphical user interface; FIG. 11 is another front view thereof, showing the right side orientation of the graphical user interface; FIG. 12 is another front view thereof, showing the left side orientation of the graphical user interface; FIG. 13 is another front view thereof, showing the top orientation of the graphical user interface; and, FIG. 14 is another front view thereof, showing the bottom orientation of the graphical user interface. The broken lines in the figures show a display screen or portion thereof, and form no part of the claimed design. The graphical user interface in FIGS. 1-7 and FIGS. 8-14 is shown in various orientations to provide an understanding of the three dimensional appearance of the design. The scope of the claim does not include any orientation or view that is not shown.
